UNITED STATES PATENT OFFICE.

WARREN W. GORE, OF MADISON, WISCONSIN, ASSIGNOR TO FULLER & JOHNSON MFG. CO., OF MADISON, WISCONSIN, A CORPORATION OF WISCONSIN.

INTERNAL-COMBUSTION ENGINE.

Application filed September 25, 1918. Serial No. 255,560.

To all whom it may concern:

Be it known that I, WARREN W. GORE, a citizen of the United States, residing at Madison, in the county of Dane and State 5 of Wisconsin, have invented certain new and useful Improvements in Internal-Combustion Engines, of which the following is a specification.

This invention relates to internal combustion engines, and has reference more particularly, although not exclusively, to single-cylinder stationary engines of the upright type such as are extensively employed as a power unit in domestic use for pumping water, generating electric current, etc.

Since gas engines of this character are generally owned and used by persons not particularly skilled in their construction and operation, it is desirable to make them not only as simple, durable and completely automatic as possible, but also to make them easy of access, especially as regards the crank-chamber and its contained parts, for inspection, cleaning, adjustment, and repairs when necessary, with a minimum of labor and trouble in the disassembling and reassembling of parts; and one of the objects of the present invention is to provide an internal combustion engine possessing in a superior degree the advantages stated. More specifically, one object of the invention is to provide a gas engine of the enclosed crank-case type, wherein the crank-case is provided with a removable side or cover plate carrying the cam-shaft and the driving mechanism of the latter, said driving mechanism being automatically engaged with and disengaged from the crank-pin of the engine shaft when the detachable side of the crank-case is applied and removed. In the most complete and approved form of the invention herein illustrated this detachable side may also carry the governing mechanism of the engine throttle. Another object of the invention is to provide in the crank-case an improved oil pan through which the lower end of the connecting rod sweeps to distribute oil to the cylinder walls on the splash principle, with a pump also located in the crank-case to maintain a supply of oil to said pan, and a pump-driving mechanism carried by said removable side of the crank-case and automatically registering

with the oil-pump plunger when the removable side is applied to the crank-case.

Other objects and advantages secured by the invention will be apparent to those skilled in the art from the following detailed description, taken in connection with the accompanying drawings wherein I have illustrated one practical embodiment of the invention, and in which—

Fig. 1 is a side elevation of the engine;

Fig. 2 is a vertical section, substantially on the offset line 2—2 of Fig. 1;

Fig. 3 is a detail view from the inner side of the detachable side plate or cover of the crank-case and parts carried thereby.

Referring to the drawings, 5 designates as an entirely the body of the crank-case 70 formed with supporting feet 6, and having a large substantially circular opening 7 at one side thereof. Superposed on the crank-case is the engine cylinder 8, equipped with the usual piston, intake and exhaust valves, 75 and ignition mechanism, with which parts my present invention is not concerned. On the opposite side of the crank-case from the opening 7 is a main bearing 9 for the engine shaft 10, on the inner end of which shaft is 80 the usual balanced crank-arm 11 carrying crank-pin 12 on which is mounted the lower end of the piston-rod 13. Keyed on the crank-shaft is a fly-wheel 14 carrying fan-blades 16 by which air is drawn down through a 85 hood 16 surrounding the cylinder to cool the latter. Beyond the fly-wheel I have indicated in Fig. 2 an electric generator 17, the armature shaft 18 of which is mounted with in the hollow engine shaft 10. Secured to 90 one side of the crank case and surrounding the fly-wheel and generator is a casing 19 formed at its outer end with a bearing 20 to receive a pulley-shaft extension of the engine shaft for power transmitting purposes, when the generator is not used.

21 designates a substantially circular plate that forms a cover or closure for the side opening 7 of the crank-case, being detachably secured to the rim of the opening by four machine screws 22 (Fig. 1). This plate 21 is formed with an integral eccentric extension 21' that, with a portion of the plate 21, constitutes the inner wall of a gear case, the outer wall of which is formed by a flanged 105 plate 23 secured to the inner wall by three

machine screws 24. On and centrally of the main cover-plate 21 is an integral inwardly extending boss 25 that forms a bearing for a hollow shaft 26, and in an opening 27 of said plate 21 is fitted a bearing sleeve 28 for the cam shaft 29, the other end of said cam shaft being journaled in a bearing sleeve 30 mounted in the opposite wall of the crank-case. Fast on the shafts 26 and 29 are the usual two-to-one gears 31 and 32. Fast on the inner end of shaft 26 is a skeleton disk 33 formed with a peripheral notch 34 (Fig. 3), that fits over the squared outer end of the crank-pin 12, being engaged with and disengaged from said crank-pin under a simple lateral movement of said disk.

Pivoted on the disk 33 are the governor levers 35, the inner ends of which abut against a sliding rod 36 mounted in the hollow shaft 26 and pressed against the thrust of the governor levers by a spring 37. The inner end of rod 36 presses, through a ball thrust bearing 38, against an aligned rod 39 slidably mounted in a bearing sleeve 40 secured in the outer end of shaft 26. The outer end of rod 39 abuts against the depending arm 41 of an elbow lever pivoted at 42 to a bracket 43 on the outer side of the gear cover plate 23, and to the horizontal arm 44 of said elbow lever is pivoted an upwardly extending rod 45 that is connected to the throttle of the carburetor (not shown). An adjustable spring 46 mounted on bracket 43 bears downwardly on the horizontal arm 44 of the elbow lever and tends to open the throttle in opposition to the closing tendency of ball-governor.

The cam shaft 29 carries the two cams 47 and 48 (Fig. 2) for operating the intake and exhaust valves of the cylinder, as usual in this type of overhead-valve engine. The cam shaft also carries an eccentric 49 for effecting the discharge stroke of an oil pump hereinafter described.

Secured to the bottom wall of the crank-case is a bracket 50 that supports an oil-pan 51 through which the lower end of the piston-rod sweeps at each revolution of the crank-shaft. This oil-pan is supplied with oil from the bottom of the crank-case by means of a pump comprising a cylinder 52, vertical plunger 53 and intake and discharge valves 54 and 55. The plunger is raised on its suction stroke by a spring 56, and is depressed on its working or discharge stroke by a rod 57 that is guided in lugs 58 on the inner face of the cover plate 21, the upper end of said rod being held in engagement with the eccentric 49 by a spring 59. On one side of the pump cylinder is pivoted a latch 60, the laterally bent upper end of which is adapted to engage over the upper end of the pump plunger to hold the same down against spring 56 when the detachable cover is being applied to the crank-case so

as to bring the lower end of rod 57 into working engagement with the upper end of the plunger. While this engagement is being effected, the latch is kicked off by a lug 61 projecting inwardly from the inner face 70 of cover plate 21.

My invention also includes an improved construction for effecting the lubrication of the main shaft bearing and the return to the crank-case of the oil that works through the main bearing. It will be observed that the main bearing 9 projects slightly inwardly of the side wall of the crank-case, and is formed on its upper side with a channel or pocket 62 to catch the oil splash, and with a duct 63 leading from said channel or pocket to the bearing. At the outer end of the main bearing is an annular channel 64 that catches the oil working through the bearing, and from the lowest point of channel 64 is a drain duct 65 drilled through a rib under the main bearing and leading into the crank-case, the inner end of said duct being provided with a check-valve 66. The crank-case is provided with the usual breather, which allows part of the air in the crank-case to discharge on the down stroke of the piston. On the up stroke of the piston a partial vacuum is formed in the crank-case which tends to create a suction through the bearings and also through the drain duct 65, thus returning to the crank-case the oil that has worked through the bearing into the oil-collecting channel 64. The check-valve 66 prevents the oil from being blown outwardly through the drain duct 65 on the down stroke of the piston. In this way a continuous circulation of oil through the main shaft bearing is maintained.

105

The principal advantage of the described construction resides in the facility and ease with which access may be obtained to the interior of the crank-case for inspection, cleaning, adjustment, or repairs, or any other purpose without partially dismantling or disassembling the various working parts of the engine. All that is necessary is to disconnect the governor-rod 45 from the throttle, remove the four machine screws 22, and withdraw the cover plate and gear casing with the parts carried thereby, as a unit, from the open side of the crank-case. This automatically disconnects the driving disk 33 of the cam-shaft and governor from the squared end of the crank-pin by a mere sliding movement. In reassembling it is impossible to disarrange the proper timing of the parts, since the registration of the notch 34 with the end of the crank-pin 12 insures the correct position of the valve cams.

120

125

130

It is believed that the foregoing will make clear to those skilled in the art the novel structural features, mode of operation, and

advantages of the present invention. Without limiting the invention to the specific details shown and described for purposes of illustration,—

5 I claim—

1. In an internal combustion engine, the combination of a crank-chamber having an engine-shaft bearing in one side wall thereof and a relatively large opening in the 10 opposite side wall, an engine shaft mounted in said bearing, a crank-arm on said shaft, a crank-pin on said arm having a free end, a detachable cover-plate for said opening, and a cam-shaft and cam-shaft driving mechanism mounted on and removable as a unit with said cover-plate, said cam-shaft driving mechanism being automatically engaged with and disengaged from the free end of said crank-pin as said 20 cover-plate is applied to and removed from said opening.
2. In an internal combustion engine, the combination of a crank-chamber having an engine-shaft bearing in one side wall there- 25 of and a relatively large opening in the opposite side wall, an engine shaft mounted in said bearing, a crank-arm on said shaft, a crank-pin on said arm having a free end, a detachable cover-plate for said opening, and a cam-shaft and cam-shaft driving mechanism mounted on and removable as a unit with said cover-plate, said cam-shaft driving mechanism including a peripherally notched rotatable element that 30 is slidable into and out of driven engagement with the free end of said crank-pin as said cover-plate is applied to and removed from said opening.
3. In an internal combustion engine, the 35 combination of a crank-chamber having an engine-shaft bearing in one side wall thereof and a relatively large opening in the opposite side wall, an engine shaft mounted in said bearing, a crank-arm on said shaft, a crank-pin on said arm having a free end, a detachable cover-plate for said opening, and a cam-shaft and cam-shaft driving mechanism mounted on and removable as a unit with said cover-plate, said cam-shaft driving mechanism being automatically engaged with and disengaged from the free end of said crank-pin as said cover-plate is applied to and removed from said opening, and a governor mechanism mounted in said cover-plate and actuated by an element of said cam-shaft driving mechanism.
4. In an internal combustion engine, the 40 combination of a crank-chamber having an engine-shaft bearing in one side wall there- of and a relatively large opening in the opposite side wall, an engine shaft mounted in said bearing, a crank-arm on said shaft, a crank-pin on said arm having a free end, a detachable cover-plate for said opening, and a cam-shaft and cam-shaft driving mechanism mounted on and removable as a unit with said cover-plate, said cam-shaft driving mechanism being automatically engaged with and disengaged from the free end of said crank-pin as said cover-plate is applied to and removed from said opening, and a governor mechanism mounted in said cover-plate and actuated by an element of said cam-shaft driving mechanism.
5. In an internal combustion engine, the combination of a crank-chamber having an engine-shaft bearing in one side wall there- 45 of and a relatively large opening in the opposite side wall, an engine shaft mounted in said bearing, a crank-arm on said shaft, a crank-pin on said arm having a free end, a detachable cover-plate for said opening, and a cam-shaft and cam-shaft driving mechanism mounted on and removable as a unit with said cover-plate, said cam-shaft driving mechanism being automatically engaged with and disengaged from the free end of said crank-pin as said cover-plate is applied to and removed from said opening, and a governor mechanism mounted in said cover-plate and actuated by an element of said cam-shaft driving mechanism.
6. In an internal combustion engine, the combination of a crank-chamber having an opening in one of its side walls, an oil-pan 50 mounted in said crank-chamber beneath and in the path of travel of the lower end of the piston-rod, a pump in said crank-chamber for supplying oil to said oil-pan, a detachable cover-plate for said opening, and operating mechanism for said pump mounted on the inner side of said cover plate and removable as a unit with the latter.
7. In an internal combustion engine, the combination of a crank-chamber having an opening in one of its side walls, an oil-pan 55 mounted in said crank-chamber beneath and in the path of travel of the lower end of the piston-rod, a pump in said crank-chamber for supplying oil to said oil-pan, a detachable cover-plate for said opening, and operating mechanism for said pump, including a shaft, an eccentric on said shaft, and a rod driven by said eccentric and actuating the plunger of said pump, all mounted on, and removable as a unit with, said cover-plate.
8. In an internal combustion engine, the combination of a crank-chamber having an opening in one of its side walls, an oil-pan 60 mounted in said crank-chamber beneath and in the path of travel of the lower end of the piston-rod, a pump in said crank-chamber for supplying oil to said oil-pan, a spring to actuate the plunger of said oil-pan, a cam-shaft and cam-shaft driving mecha- 65 nism mounted on and removable as a unit with said cover-plate, said cam-shaft driving mechanism including a peripherally notched rotatable member journaled in said cover-plate and slidable into and out of driven engagement with the free end of said crank-pin as said cover-plate is applied to and removed from said opening, and a governor mechanism mounted in said cover-plate and actuated by said rotatable member of said cam-shaft driving mechanism. 70
5. In an internal combustion engine, the combination of a crank-chamber having an engine-shaft bearing in one side wall there- 75 of and a relatively large opening in the opposite side wall, an engine shaft mounted in said bearing, a crank-arm on said shaft, a crank-pin on said arm having a free end, a detachable cover-plate for said opening, a cam-shaft journaled in said cover-plate, a gear-shaft also journaled in said cover-plate, co-operating gears on the outer ends of said shafts respectively, a gear-case attached to the outer side of said cover-plate, and a disk on the inner end of said gear-shaft having an opening to receive the free end of said crank-pin under a relative sliding movement as said cover-plate is applied to said opening of the crank-chamber, said cover-plate, shafts, gears, gear-case and disk being removable as a unit from said crank-chamber. 80
6. In an internal combustion engine, the combination of a crank-chamber having an opening in one of its side walls, an oil-pan 85 mounted in said crank-chamber beneath and in the path of travel of the lower end of the piston-rod, a pump in said crank-chamber for supplying oil to said oil-pan, a detachable cover-plate for said opening, and operating mechanism for said pump mounted on the inner side of said cover plate and removable as a unit with the latter. 90
7. In an internal combustion engine, the combination of a crank-chamber having an opening in one of its side walls, an oil-pan 95 mounted in said crank-chamber beneath and in the path of travel of the lower end of the piston-rod, a pump in said crank-chamber for supplying oil to said oil-pan, a detachable cover-plate for said opening, and operating mechanism for said pump, including a shaft, an eccentric on said shaft, and a rod driven by said eccentric and actuating the plunger of said pump, all mounted on, and removable as a unit with, said cover-plate. 100
8. In an internal combustion engine, the combination of a crank-chamber having an opening in one of its side walls, an oil-pan 105 mounted in said crank-chamber beneath and in the path of travel of the lower end of the piston-rod, a pump in said crank-chamber for supplying oil to said oil-pan, a detachable cover-plate for said opening, and operating mechanism for said pump, including a shaft, an eccentric on said shaft, and a rod driven by said eccentric and actuating the plunger of said pump, all mounted on, and removable as a unit with, said cover-plate. 110
11. In an internal combustion engine, the combination of a crank-chamber having an opening in one of its side walls, an oil-pan 115 mounted in said crank-chamber beneath and in the path of travel of the lower end of the piston-rod, a pump in said crank-chamber for supplying oil to said oil-pan, a detachable cover-plate for said opening, and operating mechanism for said pump, including a shaft, an eccentric on said shaft, and a rod driven by said eccentric and actuating the plunger of said pump, all mounted on, and removable as a unit with, said cover-plate. 120
12. In an internal combustion engine, the combination of a crank-chamber having an opening in one of its side walls, an oil-pan 125 mounted in said crank-chamber beneath and in the path of travel of the lower end of the piston-rod, a pump in said crank-chamber for supplying oil to said oil-pan, a spring to actuate the plunger of said oil-pan, a cam-shaft and cam-shaft driving mecha- 130 nism mounted on and removable as a unit with said cover-plate, said cam-shaft driving mechanism including a peripherally notched rotatable member journaled in said cover-plate and slidable into and out of driven engagement with the free end of said crank-pin as said cover-plate is applied to and removed from said opening, and a governor mechanism mounted in said cover-plate and actuated by said rotatable member of said cam-shaft driving mechanism. 135

5 pump on its suction stroke, a detachable cover-plate for said opening, operating mechanism, including a reciprocating rod engaging the outer end of said pump plunger, mounted on and removable as a unit with said cover-plate, a latch engaging said plunger to hold the same retracted and per-

mit engagement of said plunger by said rod as said cover-plate is applied to said opening, and means carried by said cover-plate 10 for disengaging said latch from said plunger after said rod has been engaged with the latter.

WARREN W. GORE.
